[57] CLAIM

The ornamental design for a data transmission terminal,
as shown and described.

DESCRIPTION

FIG. 1 is a front perspective view of a data transmission terminal showing my new design, the hinged keyboard being in the open position;

FIG. 2 is a left side perspective view thereof;

FIG. 3 is a top, front perspective view thereof;

FIG. 4 is a front perspective view of the terminal with the keyboard in the closed position;

FIG. 5 is a left side elevational view of the terminal with the keyboard in the open position;

FIG. 6 is a top plan view thereof; and

FIG. 7 is a rear elevational view thereof.
